(57) **CLAIM**

The ornamental design for a snap lock oval base connector, as shown and described.

DESCRIPTION

FIG. 1 is a top, front and right side perspective view of a snap lock oval base connector, showing our new design;

FIG. 2 is a top, rear and left side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken line showing of the environment is for illustrative purposes only and forms no part of the claimed design.
